UNITED STATES PATENT OFFICE.

LEVI PENTZ, OF CANTON, OHIO, ASSIGNOR OF TWO-THIRDS TO GEORGE N. YOHE AND JOSEPH L. HIGBY, OF SAME PLACE.

DOOR-CHECK.

SPECIFICATION forming part of Letters Patent No. 311,604, dated February 3, 1885.

Application filed September 1, 1884. (No model.)

To all whom it may concern:

Be it known that I, LEVI PENTZ, a citizen of the United States, residing at Canton, in the county of Stark and State of Ohio, have 5 invented certain new and useful Improvements in Door-Checks; and I do hereby declare that the following is a full, clear, and exact description of the same, reference being had to the annexed drawings, making a part of 10 this specification, and to the letters and figures of reference marked thereon, in which—

Figure 1 is a front view showing the check in position when the door is closed. Fig. 2 is a front view showing the check in position for 15 holding the door. Fig. 3 is a longitudinal section. Fig. 4 is a detached view of sliding bar. Fig. 5 is a detached view of frame. Fig. 6 is a detached view of tension-screw.

The present invention has relation to that 20 class of door-checks designed to hold the door at any point desired, and has for its object to provide a simple, cheap, and durable check that may be readily applied to a door as may be desired.

25 Similar letters of reference indicate corresponding parts in all the figures of the drawings.

In the accompanying drawings, A represents the frame, which is substantially of the 30 form shown in Figs. 1, 2, and 5, and is attached to the door by means of suitable screws. The bottom or lower end of this frame is open, so as to receive the head *a* on the sliding bar B, as seen in Fig. 1. The top or upper end 35 of the frame A is provided with the recess *b*, so as to admit of a longer movement of the sliding bar B. The back of the frame A is provided with a metallic plate, which fits in the frame, and is for the purpose of forming 40 a suitable bearing-surface for the sliding bar

B. This bar is provided with a slot for the passage of the screw C, and permits said bar to be moved up and down. The top of the sliding bar B is provided with a knob or handle, *d*, to operate said bar. The screw C is 45 provided with the collars D D, and between said collars is located the rubber block E, said block being small enough to pass through the opening *b*. The object of the rubber block is to provide a cushion, so as not to have the 50 sliding bar B held too rigid, and at the same time have said bar firmly hold the door in any desired position when said bar is forced upon the floor. The bottom of the head *a* may be milled, as seen in Fig. 4, if desired, or it 55 may have a smooth surface.

To operate my invention the sliding bar B is raised, as seen in Fig. 1, when it is desired to close the door. When it is desired to hold the door, the bar B is forced down, as seen in 60 Fig. 2.

I am aware that a sliding bar as applied to door-bolts is not new, and do not claim such as my invention; but

What I do claim as new, and desire to secure 65 by Letters Patent, is—

In a door-check, the combination of the frame A, provided with a movable metallic back plate and the opening *b*, of the sliding bar B, provided with the head *a* and the knob 70 or handle *d*, of the collars D D, and the rubber block E, all arranged substantially as shown, and for the purpose set forth.

In testimony that I claim the above I have hereunto subscribed my name in the presence 75 of two witnesses.

LEVI PENTZ.
